UNITED STATES PATENT OFFICE.

JOHN ERNEST MOORE, OF SOUTHPORT, ENGLAND.

KNITTING MACHINE.

Application filed March 3, 1927, Serial No. 172,335, and in Great Britain March 8, 1926.

This invention relates to the manufacture of cloth wherein the warp threads are secured to the weft threads by lock loops and has for its chief object to enable it to be made more quickly with a view to obtaining increased production. It is primarily intended for manufacturing cotton waste cloths such as are used for cleaning purposes, but various other kinds of cloth can 10 be manufactured in the same manner.

According to this invention the weft is caused to traverse the warp threads in one direction, each warp thread being crotched or lock looped around the weft thread after 15 the latter has been placed in position. If a number of sets of warp threads are arranged side by side they are traversed by a number of weft feeds which successively follow one another, the ends of the weft being cut between each two adjacent sets to produce separate widths of cloth.

In order that the said invention may be clearly understood and readily carried into effect, the same is described more fully with 25 reference to the accompanying drawings, in which:—

Fig. 1 is an elevation of part of a machine for manufacturing cloth in accordance with this invention.

Fig. 2 is a plan of part of the machine with portions broken away.

Fig. 3 is an elevation of part of the machine with a portion broken away.

Fig. 4 is a vertical section taken approximately on line 4—4 of Fig. 2 of part of the machine.

Fig. 5 is an elevation of a warp creel and letting off motion.

Fig. 6 is an elevation showing a construction of part of Fig. 5 and a weft cutting appliance.

Fig. 7 is an elevation of a cloth beam and mechanism for rotating it.

Fig. 8 is a plan of part of two cam plates.

Fig. 9 is a detached view of a knitting needle element drawn to a larger scale.

Fig. 10 is a section taken on line 10—10 of Fig. 9.

Fig. 11 is an end elevation of the needle element, and

Figs. 12 to 19 are progressive views showing a warp thread being crotched or lock looped around a weft thread.

A indicates the weft and B the warp. In 55 the example shown the machine is constructed to manufacture six lengths of cloth

at one operation and for this purpose six separate weft supplies in the form of cops a are mounted on a rotary table C, the weft being drawn in an axial direction from the cops through guide eyes a¹. Each weft thread is then taken through a lower guide eye a² to a weft carrier a³ comprising a tube or an inverted channel shaped guide which inclines at its forward end and is attached 60 to an arm a⁴ that is adjustably mounted on the table C. This weft carrier travels along an annular space a⁵ between two rails D and E. The rail D is fixed to a stationary table F carried by vertical frames f and provided 70 with a bearing f¹ for a central shaft G which carries the rotary table C, guide eyes a¹ and cam plates hereinafter described. The rail E is made in the form of a channel and carries a number of warp supporting members 75 b each of which is bored at b¹ and formed with an aperture b² for the passage of a warp thread B as shown more particularly in Figs. 12 and 13. The rail E is fixed to brackets e carried by upright rods e¹ which are supported from the frames f by adjustably mounted brackets e². Each warp 80 thread B, comes from a bobbin b³ on a creel b⁴, is taken over a guide roller b⁵ and between two rods b⁶ b⁷. The rod b⁷ is stationary, 85 and the rod b⁶ is moved to and fro to let off warp from the bobbins as and when required during the formation of the lock loop. For this purpose the rod b⁶ is carried by two end frames b⁸ that are pivotally mounted about 90 the rod b⁷ and moved in one direction by a rod b⁹ against the action of a spring b¹⁰ which moves the end frames and rod b⁶ in the other direction. The lower end of the rod b⁹ is connected to a crank b¹¹ (Fig. 4) 95 on a rod b¹² which is free to turn in a bracket b¹³ that is adjustably secured to the vertical frame f. Projecting from the rod b¹² is a finger b¹⁴ which is actuated by a cam b¹⁵ to lift the rod b¹², a number of such cams being mounted on a cam plate b¹⁶ fixed on the central shaft G. Each warp thread after passing the rod b⁷ is threaded through the aperture b² in the warp supporting member b where it is united with the weft threads A by latch needles H, one set of needles being provided for each piece of cloth. Each needle H is eccentrically or otherwise mounted in a needle carrier h¹ slidably mounted in rails h¹ which are fixed to the stationary 100 table F. Each needle carrier is provided with a stud h² which is acted upon by cam

surfaces h^3 , h^4 on the underside of the table C for imparting a backward and forward movement to the needle carrier and needle. Each cam stud is fixed on a vertical bracket 5 h^5 (Fig. 11) mounted on a sleeve h^6 (Fig. 9) through which the needle carrier passes. To prevent the cam stud from turning about the axis of the needle carrier the lower end of the bracket is slotted at h^7 (Fig. 11) to enable 10 gage a guide h^8 (Fig. 4) which is arranged parallel with the needle carrier. To prevent relative endwise movement of the needle carrier and sleeve and allow the needle carrier to turn in the latter, each sleeve is 15 slotted transversely at h^9 (Figs. 9 and 10) for the passage of a screw h^{10} or pin which projects through such slot. When this screw or pin is removed, the needle carrier can be drawn out of the machine. Each needle 20 carrier is arranged to receive a partial turn in alternate directions in addition to the backward and forward movements. This is conveniently effected by providing each needle carrier near its inner end with two pins 25 h^{11} arranged at an angle to one another. These pins operate in conjunction with plane surfaces h^{12} fixed at intervals to a table h^{13} which is fixed on the shaft G and rotates therewith. Fixed to the table h^{13} 30 above the gap which exists between each two of the surfaces h^{12} is an arm or plate h^{14} . The pins h^{11} together with the aforesaid plane surfaces, gaps and plates cause the needles to be turned positively in alternate 35 directions as and when required and held positively in the positions to which they have been turned. After each needle has completed its forward stroke and is beginning to return, it is turned over to a position 40 in which the hook will engage a warp thread and draw it inwardly over the inner guide rail the needle again turning to cause the hook at the end to occupy its upright position on its inward stroke. The weft carrier 45 now carries the weft past the loop of warp that is suspended from the needle clear of the end of the latch and depresses a portion of the warp thread below the two guide rails leaving the weft on the top of such 50 thread. This position is shown clearly in Fig. 12. The needle then moves outwardly as shown in Figs. 14 and 15, the latch being turned over by the first loop as the needle slides through it. By the time the needle has 55 arrived at the end of its outward stroke, the rear end of the weft carrier has left the needle as shown in Fig. 16. The needle then commences its return stroke and is again turned as shown in Fig. 17 to take another 60 loop of warp thread and draw it through the loop that is on the needle and which now slips off as shown in Fig. 18, a portion of the warp thread still being retained on the hook of the needle. It will now be seen that a 65 lock loop has been formed in the warp

around the weft. As each warp thread is drawn inwardly by the needle hook, the weft is prevented from being drawn inwardly by a series of pins d which project upwardly on the inner rail D. After the weft 70 has been deposited, it is automatically cut in suitable proximity to the edge of the cloth. For this purpose a cutter J mounted on a bracket j attached to the stationary table F may be actuated by link and lever connections j^1 from a rod j^2 that is connected at its upper end to one of the end frames b^8 that is rocked in the manner previously described. Each time a weft carrier has travelled past a set of warp threads a taking up 75 motion is actuated to take up the cloth. In the example shown this taking up motion comprises a roller K which is shown made in two lengths and has fixed to it at each end a ratchet wheel k , the said roller being carried 80 by a shaft k^1 supported in brackets k^2 that are attached to the upright rods e^1 . Slidably mounted in lugs on each of such brackets is a rod k^3 carrying a pawl k^4 that is caused to engage its ratchet wheel by a 85 spring k^5 , and operating in conjunction with such pawl is a spring controlled retaining pawl k^6 mounted on a rod k^7 which extends across the top of the roller K. Passing through an eyelet in a portion of the rod k^8 90 is one end of a two-armed lever k^8 that is pivotally mounted on the frame f. The other arm of this lever is steadied by a guide post k^9 and carries a roller k^{10} that rides over a series of cams k^{11} on a cam plate k^{12} that 95 is rigidly fixed on the central shaft G. Each time one of these cams passes under one of the rollers k^{10} it lifts the corresponding lever k^8 and actuates the pawl k^4 to advance 100 the ratchet wheel. When the taking up roller is made in two sections two sets of cams k^{11} are provided one set for each section the said cams being so arranged that the two parts of each roller are actuated successively. The cloth passes under the taking up roller 105 K over the rod k^7 to a beam or cloth roller L (Figs. 1 and 7) which is rotatably mounted in brackets l secured to the upright rods e^1 . This beam is rotated simultaneously with the taking up roller K by a pawl l engaging a ratchet wheel l^2 on the beam or rotating with it and actuated by a bell crank lever l^3 that is maintained in contact with the lower end of the rod k^8 by a spring l^4 . The pawls for actuating the taking up and 110 cloth rollers are returned to their initial positions by a spring k^{13} . If desired a friction device may be applied to the cloth beam L for keeping the fabric taut. 115

What I claim as my invention and desire to secure by Letters Patent in the United States is:

1. In a machine for manufacturing cloth of the character specified, means for guiding a circle of warp threads, means for travers- 120

130

- ing a weft thread around the circle of warp threads, a circle of radially mounted latch needles, and means for imparting endwise reciprocating and opposite turning movements to said needles to crotchet the warp threads around the weft thread as the latter traverses the circle of warp threads.
2. In a machine for manufacturing cloth of the kind specified, means for guiding a circle of warp threads, means for traversing a weft thread around the circle of warp threads, means for crocheting the warp threads around the weft thread as the latter traverses the circle of warp threads, means for cutting the cloth into sections, a cloth taking up motion comprising a roller made in sections for the sections of cloth, and means for turning each roller section successively.
- 20 3. In a machine for manufacturing cloth of the kind specified, means for guiding a circle of warp threads, means for traversing a weft thread around the circle of warp threads, a circle of radially mounted latch needles and rotatable and slid able carriers for said needles, each carrier having two pins arranged at an angle to one another,

and a rotary device having spaced surfaces and arms at the spaces between said surfaces, said surfaces and arms moving across opposite sides of said carriers and being adapted to contact with said pins to rotate the carriers and needles in opposite directions, and said device having means to reciprocate the needles, so that the reciprocatory and rotary movements of said needles will crotchet the warp threads around the weft thread.

4. In a machine for manufacturing cloth of the character described, means for guiding a circle of warp threads arranged in sets for a plurality of sections of cloth, means for traversing a weft thread around the circle of warp threads, means for crocheting the warp threads around the weft thread as the latter traverses the circle of warp threads, means for cutting the weft thread between the sets of warp threads, and a cloth taking up motion having a plurality of sections, one for each section of cloth, operable in succession in cooperation with the second named means.

In witness whereof I have signed this specification.

JOHN ERNEST MOORE.
